UNITED STATES PATENT OFFICE.

JOHN H. LEPPART, OF ROME, NEW YORK.

MOP-HOLDER.

1,192,330.

Specification of Letters Patent. Patented July 25, 1916.

Application filed March 18, 1916. Serial No. 85,078.

To all whom it may concern:

Be it known that I, JOHN H. LEPPART, a citizen of the United States, residing at Rome, in the county of Oneida and State 5 of New York, have invented certain new and useful Improvements in Mop-Holders; and I do hereby declare the following to be a full, clear, and exact description of the invention, such as will enable others skilled 10 in the art to which it appertains to make and use the same.

This invention relates to new and useful improvements in a mop holder especially adapted for cleaning flushing bowls of toilets 15 and bed pans and one of its objects is the provision of a device of this character, which shall be simple, durable and efficient, and which may be manufactured and sold at a comparatively low cost.

Another object of this invention is to provide a sleeve having a downwardly and outwardly inclined stationary jaw formed thereon of substantially circular formation to which is pivoted a movable jaw for 20 operation with the downwardly inclined jaw to grip a piece of cloth or any other suitable material to provide a mop.

A further object of this invention is to provide the stationary jaw with a downwardly inclined serrated gripping face for 25 coöperation with the serrated gripping face of the pivoted jaw to efficiently grip the cloth or other piece of material to prevent it from pulling between the jaws when in 30 use.

A still further object of this invention is to provide a curved rod secured to the pivoted jaw and passing upwardly through the stationary jaw and pivotally secured to an 35 operating lever having a cam action carried by the sleeve for drawing the pivoted jaw upwardly into an engagement with the stationary jaw and lock said pivoted jaw against movement, to prevent the mop cloth 40 from becoming accidentally disengaged from the jaws.

With these and other objects in view as will become more apparent as the description proceeds, the invention consists in certain 45 novel features of construction, combination and arrangement of parts as will be hereinafter more fully described and claimed.

For a complete understanding of my invention, reference is to be had to the follow-

ing description and accompanying drawing, in which:

Figure 1 is a side elevation of a mop holder, constructed in accordance with my invention, Fig. 2 is a front elevation of the 60 same. Fig. 3 is a front elevation of the stationary jaw removed from the handle, Fig. 4 is a longitudinal sectional view taken on the line 4—4 of Fig. 1, and Fig. 5 is a fragmentary longitudinal sectional view of 65 the stationary jaw, illustrating the downwardly inclined serrated gripping face.

Referring in detail to the drawing, the numeral 1 indicates a handle and 2 an eye-bolt for suspending the handle 1 on a hook 70 or nail when not in use. A sleeve 3 consisting of sections 4 and 5 is secured to the end of the handle 1 by a set screw passing through the sections 4 and 5 of the sleeve 3 and the handle 1.

Formed on the lower end of the section 4 of the sleeve 3 is a downwardly and outwardly inclined stationary jaw 7 of substantially circular formation, having its gripping face curved downwardly as illustrated 80 at 8 and provided with a plurality of notches 9 to form a serrated gripping face.

Formed on the section 4 of the sleeve 3 is a projection 10 which is apertured to receive a pin 11. A substantially circular jaw 12 85 is provided with relatively spaced ears 13 which are apertured to receive the pin 11 upon each side of the projection 10, to provide a hinged jaw. The hinged jaw 12 is provided with a plurality of notches 14 to 90 provide a serrated gripping face to co-operate with the serrated gripping face of the stationary jaw 7. A projection 15 is formed on the hinged jaw 12 adjacent the ears 13 and oppositely disposed thereto. 95 The projection 15 is apertured and has one end of a curved rod 16 secured thereto, which extends upwardly through the stationary jaw 7. An apertured lug 17 is formed on the section 5 of the sleeve 3 and 100 has pivotally secured thereon an operating lever 18 to which the free end of the rod 16 is secured. The operating lever 18 is bent at right angles intermediate its ends 105 to provide a handle 19 for swinging the operating lever upon its pivot.

In operation, a piece of mop cloth or other suitable material (not shown) is placed between the jaws 7 and 12 and by pulling upwardly upon the operating lever 18, the 110

hinged jaw 12 will be brought into an engagement with the stationary jaw 7 and locked by the cam action of the operating lever 18. The device then may be used to clean out any article or receptacle and when the mop cloth becomes soiled it may be dropped directly into a fire and destroyed without the necessity of the user placing his hands thereon. By swinging the operating lever 18 downwardly, the hinged jaw 12 will be moved downwardly and free the mop cloth.

While I have shown and described the preferred embodiment of my invention, it will be understood that minor changes in construction, combination and arrangement of parts may be made without departing from the spirit and scope of the invention as claimed.

Having thus described my invention, what I claim is:—

1. A mop holder comprising a handle, a sleeve detachably secured to one end of the handle, a substantially circular jaw formed on the lower end of the sleeve and extending downwardly and outwardly therefrom, a substantially circular jaw pivoted to the sleeve adjacent the stationary jaw, said jaws provided with a plurality of notches to form serrated gripping faces, and means carried by the handle and secured to the movable jaw for bringing said jaw into engagement with the stationary jaw.

2. A mop holder comprising a handle, a sleeve detachably secured to the lower end of the handle, a substantially circular jaw formed on the sleeve and extending downwardly and outwardly therefrom, said jaw provided with its edges curved downwardly and notched to provide serrating gripping faces, a movable jaw pivoted to the sleeve adjacent the stationary jaw and provided with a plurality of notches to provide a serrated gripping face, and means carried by the sleeve and extending to the stationary

jaw and secured to the pivoted jaw for moving said pivoted jaw into an engagement with the stationary jaw.

3. A mop holder comprising a handle, a pair of sections secured to the lower end of the handle to form a sleeve, a substantially circular jaw formed on one of said sections and extending downwardly and outwardly therefrom to provide a stationary jaw, a projection formed on the last mentioned section of the sleeve adjacent the stationary jaw, a substantially circular jaw pivoted on the lower end of said sleeve to provide a movable jaw, a curved rod secured to the movable jaw and extending to the stationary jaw, and means carried by one of the sections of the sleeve and connected to the free end of the curved rod for moving the movable jaw into an engagement with the stationary jaw.

4. A mop holder comprising a handle, a sleeve detachably secured to the lower end of the handle, a substantially circular jaw formed on the lower end of the sleeve and extending downwardly and outwardly to provide a stationary jaw, a movable jaw pivotally secured to the lower end of the sleeve adjacent the stationary jaw, said jaws provided with notches to form serrated gripping faces, an operating lever pivotally secured to the sleeve adjacent the upper end thereof, a curved rod pivotally secured to the movable jaw and extending upwardly through the stationary jaw and secured to the operating lever for moving the movable jaw into an engagement with the stationary jaw when the operating lever is swung upwardly.

In testimony whereof I affix my signature in presence of two witnesses.

JOHN H. LEPPART.
